UNITED STATES PATENT OFFICE

148,189

DESIGN FOR AN ASH TRAY

Philip Victor Rommel and Joseph A. French,
Newark, N. J.

Application July 1, 1946, Serial No. 131,236

Term of patent 3½ years

(Cl. D85—2)

To all whom it may concern:

Be it known that we, Philip Victor Rommel, a citizen of the United States, residing in Newark, county of Essex, and State of New Jersey, and Joseph A. French, a citizen of the United States, residing in Newark, county of Essex, and State of New Jersey, have invented a new, original, and ornamental Design for an Ash Tray, of which the following is a specification, reference being had to the accompanying drawing, forming part thereof.

In the drawing:

Fig. 1 shows a top view of an ash tray illustrating our new design;

Fig. 2 shows the same ash tray in side elevation;

Fig. 3 is an end view.

We claim:

The ornamental design for an ash tray, as shown.

PHILIP VICTOR ROMMEL.
JOSEPH A. FRENCH.
